UNITED STATES PATENT OFFICE.

MALCOLM T. HEIL AND CLIFTON T. HEIL, OF ALLENTOWN, PENNSYLVANIA.

SAFETY-RAZOR.

No. 908,568.

Specification of Letters Patent.

Patented Jan. 5, 1909.

Application filed February 21, 1908. Serial No. 417,142.

To all whom it may concern:

Be it known that we, MALCOLM T. HEIL and CLIFTON T. HEIL, citizens of the United States, residing at Allentown, in the county of Lehigh and State of Pennsylvania, have invented certain new and useful Improvements in Safety-Razors, of which the following is a specification.

This invention comprehends certain new and useful improvements in safety razors, and the invention has for its primary object an improved device of this character which will possess to a marked degree the characteristics of simplicity and durability of construction, and efficiency of operation, in that the blade and guard are of elongated diamond shape with a handle rigidly, though detachably secured thereto and extending at right angles therewith, the shape of the blade affording a maximum shaving surface as well as affording means whereby an effective shearing cut may be secured without changing or adjusting the position of the handle, whereby a portion of the edge passing over the face will be followed by other portions of such edge in a shearing stroke, so as to practically go over the face a number of times with the one and same operation, and whereby, by a simple axial movement of the handle without any adjustment thereof, the said blade may be turned or rocked on the face from one edge to an adjacent edge forming an obtuse angle therewith, so as to effectively change the position of the blade in passing from one portion of the face to another, as from the cheek, around the cheek bone to the neck, without removing the razor from the face.

Our invention also has for its object an improved safety razor in which the parts are rigidly, though detachably connected together in such a manner that none of the fastening means are exposed or in the way, which will permit the parts to be readily cleansed and easily assembled without danger of breaking any of the parts or of cutting one's hand with the blade in applying the same.

A further object of the invention is a device of this character which is so arranged that any desired thickness of blade may be employed, from a wafer blade to a comparatively heavy one, the blades being secured in place and held in a rigid position relative to the guard or body portion of the device.

The invention also has for its object an

improved construction of safety razor, which, owing to the shape of the blade and guard as above described, with its acute points renders it peculiarly adaptable for shaving certain parts of the face, such as under the nostrils and around the ears and neck, which would be impossible with a safety razor of other shape. And a further object of the invention is a device of this type provided with an improved construction of strop device whereby a section of the handle may be removed from the body portion or guard and secured to a blade holder so that the blades may be resharpened by stropping or honing, and thereby increase their usefulness.

With these and other objects in view as will more fully appear as the description proceeds, the invention consists in certain constructions, arrangements and combinations of the parts that we will hereinafter fully describe and then point out the novel features thereof in the appended claims.

For a full understanding of the invention and the merits thereof, reference is to be had to the following description and accompanying drawings, in which:

Figure 1 is a perspective view of our improved safety razor; Fig. 2 is a similar view of the parts detached and in juxtaposition to each other; Fig. 3 is a longitudinal sectional view through the device; Fig. 4 is a perspective view illustrating the handle and the blade holder connected together for use in resharpening a blade; and, Fig. 5 is a horizontal sectional view on the line 5—5 of Fig. 3.

Corresponding and like parts are referred to in the following description and indicated in all the views of the drawings by the same reference characters.

Referring to the drawing, the numeral 1 designates the body portion or guard plate of our device, the same being formed in its margin with guard teeth 2 of any desired number, size as to depth, or thickness, and shape. Rigidly and preferably permanently connected to the guard plate 1 is a hollow handle section 3, the said plate being formed with an opening communicating with the interior of said section. The plate 1 is formed on its upper or outer side with two relatively short studs 4 upon opposite sides of and in alinement with the said opening that communicates with the handle section 3. These studs 4 are designed to fit in openings 5 formed in the blade 6 which corresponds in

shape to the plate 1, although, manifestly, being slightly smaller than said plate, so that when it fits thereon and is held securely in place by the studs 4, the guard teeth 2 will 5 project beyond the cutting edges of the blade to the proper extent. In addition to the openings 5, the blade 6 is formed with a relatively large opening 7 designed to register with the opening through the guard. 8 designates a cap plate which also corresponds in shape to the guard plate 1 and blade 6, although relatively smaller than the same and said cap plate is formed in its underside with two relatively shallow sockets 8^a preferably 10 located in a concavity in the said lower face of the cap plate, as best illustrated in Fig. 2. These sockets 8^a are designed to receive the ends of the studs 4 when the cap plate is applied to the guard plate 1, so as to securely 15 hold the interposed blade 6.

9 designates a stem which is preferably rigidly secured to the cap plate 8 and which is designed to pass through the opening 7 in the blade and down into the hollow handle 25 section 3. The stem 9 is formed with a threaded extremity 9^a and is of such a length proportionate to the hollow handle section 3 that a portion of said threaded extremity 9^a will protrude from the lower end of the 30 handle section 3 when the blade and cap plate are in proper operative position, as illustrated in Fig. 3.

In order to hold the cap plate in position to clamp the blade solidly upon the plane 35 surface of the guard plate 1, we provide the main hollow section 10 of the handle which is formed at one end with a slip socket 11 by which it may be readily slipped over the reduced neck 3^a formed on the lower end of the 40 complementary handle section 3. At the base of this slip socket 11, the main handle section 10 is internally threaded, as indicated at 12 (Fig. 3), the said threads being designed to engage with the threaded extremity 9^a of the stem 9 so as to securely hold the 45 parts together. It is to be particularly noted that when the parts are held in position (see Fig. 3), none of the fastening means are exposed or in any wise in the way, and the 50 blade 6, whether it be a wafer blade, or a thick blade, is held rigidly in an unflexed and plane condition by such fastening devices, down upon the guard plate 1.

13 designates a blade holder which is formed 55 with a longitudinal slit 14 extending longitudinally thereof from one end and terminating short of the other end. The last named end of the blade holder is reduced and threaded as indicated at 15, and is designed to fit in a 60 correspondingly formed socket in the end of the main handle section 10 opposite the split socket 11. The opposite end of the blade holder 13 is reduced and threaded as indicated at 16, and a screw threaded cap 17, 65 preferably of less diameter than the main or

body portion of the blade holder is designed to be screwed over the said end 16, so as to clamp a blade in the slit 14 after the blade holder has been applied to the handle section 10, so that the holder and section together 70 may serve as a convenient device for holding the blade in a position for stropping or honing the same.

From the foregoing description in connection with the accompanying drawing, it will 75 be seen that we have provided a very simple, durable and efficient construction of safety razor; owing to the diamond-like formation of the guard plate and blade, a maximum cutting surface is afforded, while at the same 80 time, a shearing cut may be secured without any necessity of adjusting the blade to different inclinations or angles relative to the handle, the blade being at all times held in a plane at right angles to the length of the 85 handle and being secured firmly in place by fastening means that are not exposed. The construction at the same time enables the parts to be readily detached one from the other and cleansed, and as readily reassembled, it being only necessary, in assembling 90 the parts, to hold the blade flat in the palm of one hand, without any danger of cutting one's hand and to then apply the guard plate by holding it by its handle section 3 in the 95 other hand, so as to slip the studs 4 into the opening 5, whereupon the parts may be inverted and the blade caused to rest securely on the upper surface of the guard plate 1, while the stem 9 is slipped through the opening 7 and into the handle 3, so as to apply the 100 cap plate 8, the main section 10 of the handle being then slipped over the neck 3^a and secured to the extremity 9^a, in order to rigidly hold the parts together. 105

Having thus described the invention, what is claimed as new is:

1. A safety razor, comprising a guard plate formed on its upper side with studs, and an opening between and in alignment with said studs, a hollow handle section secured to said plate in registry with said opening, a blade adapted to rest on said plate and formed with openings adapted to receive said studs, and with an intermediate opening 110 adapted to register with the opening in the plate, and a cap plate adapted to rest upon the upper surface of the plate and formed with sockets receiving the ends of said studs, said cap plate being provided with a stem 115 designed to extend through the opening in the plate and through the hollow handle section and designed to hold the blade upon the guard plate, and a complementary handle section, adapted to slip over the end of the 120 first mentioned handle section and arranged for engagement with the said stem whereby to draw it firmly upon the blade and clamp the latter between the cap plate and guard plate. 125 130

2. A safety razor, comprising a guard plate formed on its upper side with studs, a perforated blade arranged to rest upon said guard plate, with the studs passing through the perforations, a cap plate adapted to rest upon the blade and formed in its lower face with sockets terminating short of the upper face of the cap plate, and receiving the studs, means for clamping the cap plate upon the blade, and a handle.
3. A safety razor comprising a guard plate, a blade adapted to rest upon said guard plate, a cap plate adapted to rest upon the blade, a handle section secured to said guard plate, a stem secured to the cap plate and passing through the blade and guard plate and through the handle section with a lower threaded extremity protruding from the lower end of the handle section, said handle section being provided at its lower end with a reduced neck and a complementary handle section provided with a slip socket by which it is adapted to be slipped over the reduced neck, and formed below said socket with interior threads designed to engage the threaded extremity of the stem as and for the purpose set forth.
